UNITED STATES PATENT OFFICE

2,133,710

BOX FOR PENCILS AND THE LIKE

Roy E. Lowey, Evanston, Ill., assignor to Horder's
Incorporated, Chicago, Ill., a corporation of
Illinois

Application December 19, 1936, Serial No. 116,746

6 Claims. (Cl. 206—67)

This invention relates to a box for the accommodation of pencils or like articles, and for the partial display of such articles when they are positioned within the box. As shown, it comprises two units, viz., a tray and an open-ended tubular enclosure therefor, there being a window in the latter permitting a view of the contents within the tray.

It is a primary object of my invention to construct a box in which is provided a cushion support for a number of articles, such as pencils, by which they will be protected during all stages of their shipping, handling and display. The pencils herein shown and described are of the common variety having a wooden body one end of which is sharpened from time to time to expose the lead. It is not possible to pre-sharpen pencils of this character with any assurance that the exposed leads will be intact at the time the pencils reach the consumer. In the course of shipping and handling the exposed leads are very apt to become broken even though they be packed in a protecting material, such as cotton or the like.

According to the improvements which are incorporated into the present box, pre-sharpened pencils may be shipped, handled and sold in boxes wherein a quantity of such pencils are contained, all without danger of lead breakage. This is due to certain peculiarities in the construction by which the several pencils are cushion-supported under compression in such a manner as to be immune from any direct transmission of shocks. In the production of boxes having such features of protection, I may utilize an appropriate paper board having the requisite tension properties, which is cheap, easily converted, light in weight, and which is otherwise adaptable to the purposes of this invention.

Certain suggestive embodiments of my invention are set forth in the accompanying drawing in the manner following:

Figure 1 is a view in plan, with the tubular enclosure in an off-center position, a portion of its top wall being broken away to show a single pencil mounted in place within the tray;

Fig. 2 is a longitudinal vertical section therethrough on line 2—2 of Fig. 1;

Fig. 3 is a transverse section therethrough on line 3—3 of Fig. 1;

Fig. 4 is a view of the blank from which the tray is made, the outer side sections being folded over to lie upon the blank;

Fig. 5 which is a view similar to Fig. 1 shows a similar pencil box having a slightly modified construction;

Fig. 6 is a central longitudinal section taken on line 6—6 of Fig. 1; and

Fig. 7 is a view of the blank from which the tray of Fig. 5 is made, the outer side sections of the blank being bent over and folded down thereupon.

One unit of the present box is in the general form of a tray, and is designated as T. It may be formed from a blank (see Fig. 4) having outer side sections 10 adapted to be folded along score lines a. These sections constitute inner side walls for the tray (see Fig. 3). Near the free edge of each folded section 10 is a score line b which defines the bend along the lower corner of the tray. At the rear end of the tray I provide three score lines c, d and e spaced about evenly from each other. Between the lines c and d is formed a section 11 adjacent which is a second section 12 between the lines d and e, and beyond the line e is an end section 13. The opposite ends of these sections are defined by cuts f which, as shown, are aligned with the score lines b. Each cut may be slightly offset at the score line d, so that the two sections 14 lying to the outside of these cuts are slightly narrower in the regions opposite the sections 12 and 13.

At the forward end of the tray I provide offset cuts g corresponding in position to the cuts f, the sections 15 thus defined being traversed by score lines h, i and j which extend continuously across the blank. Between the lines h and i is defined a section 16. A section 17 between the lines i and j lies adjacent thereto, and beyond the line j is a wide flap section 18 separated by a score line k from a section 19 with score lines l in line with the cut g defining opposite end tabs 20.

A blank of this description may be erected into a tray structure as shown in Figs. 1, 2 and 3. When set up, the two sections 14 are swung through 90° into overlapping relation; the section 11 is bent into a vertical position so as to lie outside of the overlapping sections 14; the section 12 is then bent down to lie upon the inside of the overlapping sections; and the section 13 is then extended horizontally upon the floor of the tray. At the opposite end, the two sections 15 are swung through 90° to lie in overlapping relation; the section 16 is then swung upwardly to lie outside of these overlapping sections; the section 17 is then bent down to lie inside of these overlapping sections; and the flap section 18 is then extended along the floor of the tray to present the section 19 at a point which is removed from the tray end. The section 19 is

- bent upwardly to a vertical position, the two tabs 20 being bent around through 90° to lie upon the inside of the side walls which are constituted by the sections 10 when bent upwardly 5 along the score lines b.
- The resulting tray, formed from a blank which is cut and scored as above described, is characterized by side walls of two plies which, if desired, may be adhered together; by a rear end 10 wall of overlapping disconnected sections which are confined between hinged outer and inner plies, the latter having a flap extending along or just above the floor of the tray; and by a forward wall which comprises disconnected overlapping 15 sections confined in place by hinged outer and inner plies, the latter having a wide flap which is extended along or just above the floor of the tray to support a hinged bridge wall with tabs extended laterally from opposite ends thereof.
- 20 These tabs serve as stops to prevent the bridge being bent appreciably beyond a vertical position (see Fig. 2). The inner plies at opposite ends of the tray, which are tensioned by their respective hinge connections, normally extend obliquely 25 into the tray. Likewise the bridge wall is similarly tensioned, normally inclining toward the remote end wall. Advantage is taken of this tensioning of the end and bridge walls in a manner that will now be explained.
- 30 As shown, the bridge wall is provided with a number of perforations 21 arranged preferably in double rows. These perforations are of a size to support and abut one end of an accommodated implement, as, for example, the cone point 22 of 35 a pre-sharpened pencil P whose length is such that its opposite end may abut the rearward wall of the tray. If the pencils be equipped with erasers E, as shown in the drawing, then the erasers will engage with the rear wall. The exposed lead 23 lies wholly between the bridge wall 40 and the front end of the tray, and is protected from any shocks that might be transmitted to the bridge wall by the surrounding cone body at the pointed end of the pencil. A number of 45 such pencils, perhaps a dozen, may be accommodated in place, each having its cone end inserted through one of the bridge wall openings 21. The disposition of these holes, as shown in Fig. 2, may be such that pencils in the lowermost row 50 will be suspended at their pointed ends slightly above the floor of the tray, thereby receiving protection against direct transmission of any shocks proceeding from that direction. When so disposed, the bridge wall, by its own spring action, will tend to advance upon and abut the cone end of the pencils, thereby causing the pencils to be subjected to a thrust force which proceeds toward the rear wall of the tray. As above explained, this wall comprises an inner ply which 55 tends to spring inwardly, thereby co-operating with the bridge wall to support the pencils under compression. In this way the several pencils are centered, as to their cone ends, by the holes in the bridge wall, and by this wall and the opposite end wall are suspended in place so as to be 60 protected against shocks which may be transmitted to the tray from the direction of either end. The flap section 18 from which the bridge wall is extended may be extended at its ends just 65 below the free edges of the side sections 10, whereby to be secured in an operative position close to the tray bottom.
- The enclosure C for the tray, as already indicated, may comprise an open-ended tube of a 70 size and shape to closely surround the tray with

which it is slidably associated. The tube may be equipped with an open window 24 covered by a thin transparent sheet, affording a view of the pointed ends of the pencils within the box. An attractive display package is thereby provided 5 and one which apprises customers concerning the condition of the pencils which are offered for sale.

In the construction of box illustrated in Figs. 5, 6 and 7, the side and rear walls may be the 10 same as already described, and accordingly are designated by corresponding reference numerals. At the front end, however, I omit the section 19 and tabs 20 forming the bridge wall assembly. Instead, there is provided in the tray bottom a 15 three-sided slit 25 which extends slightly into the area beyond the score lines b, to define a bridge wall 26 with foldable end flaps 27. This bridge wall which is perforated may then be swung upwardly from the tray bottom, as shown 20 in Fig. 6, to a substantially vertical position, the flaps being bent laterally toward the front wall and engaging with the section 18 along the tray bottom to serve as stops for swinging movement 25 of the bridge wall beyond the intended point. In this construction the bridge wall is tensioned to swing back toward the rear wall, thereby exerting upon the supported pencils a thrust force which is directed against the inner ply of the rear wall which is also tensioned to swing inwardly in the manner already explained. The support and protection afforded to the pencils contained in this box is substantially the same as that already described.

I claim:

1. An implement box in which is comprised a tray having multi-ply end walls, a bridge wall connected to an inner ply of one end wall and spaced therefrom and tensioned to swing toward the opposite end of the tray, the distance between 40 the bridge wall and the said opposite end of the tray being such as to compress therebetween an implement having one end fitted against the bridge wall and its opposite end abutting the remote end of the tray.

2. An implement box comprising a tray, a perforated bridge wall extended transversely across the tray in spaced relation to one end thereof adapted to support and abut one end portion of an implement whose remote end lies adjacent the 50 opposite end wall of the tray, and tension means between the said opposite end wall and the adjacent end of the implement for maintaining the same under compression against said bridge wall.

3. An implement box comprising a tray, an end wall having an inwardly folded extension on its inner side and a bridge wall portion upwardly folded from its inner end so as to normally swing under the tension of the fold toward the opposite end of the tray, said bridge wall extending transversely across the tray and adapted to support and abut one end of an implement whose opposite end abuts the remote tray end by which the implement is maintained under compression 60 therebetween.

4. An implement box comprising a tray, a bridge wall having a tensioned swinging mounting transversely of the tray, abutment means cooperating with the bridge wall and tray for limiting swinging movement of the bridge wall beyond a predetermined point toward one end of the tray, and means associated with the bridge wall adapted to support and abut one end portion of an implement whose opposite end abuts the remote end of the tray.

5. A box for holding sharpened pencils comprising a tray, a bridge wall extending transversely of the tray adjacent one end thereof adapted to abut and support the sharpened end portions of the pencils whose opposite ends abut the remote end of the tray, and means providing a yieldable mounting for the bridge wall tensioned to normally swing the wall toward said remote end of said tray.

10 6. A box for holding sharpened pencils having

a bottom and spaced walls in opposition, and a bridge wall folded up from the bottom adjacent one end wall and tensioned by the fold to normally swing toward the opposite end wall, said bridge wall having means adapted to forcibly abut the sharpened ends of pencils whose opposite ends abut said opposite end wall in maintaining said pencils under compression therebetween.
